UNITED STATES PATENT OFFICE.

GEORGE R. MULHOLLAND, OF RIVERSIDE, NEW JERSEY, ASSIGNOR TO THE KEYSTONE WATCH CASE COMPANY, OF PHILADELPHIA, PENNSYLVANIA, A CORPORATION OF PENNSYLVANIA.

REMOVABLE-BAR HANGER FOR STRAP ENDS.

Application filed January 13, 1923. Serial No. 612,532.

To all whom it may concern:

Be it known that I, GEORGE R. MULHOLLAND, a citizen of the United States, and a resident of Riverside, in the county of Burlington and State of New Jersey, have made and invented certain new and useful Improvements in Removable-Bar Hangers for Strap Ends, of which the following is a specification.

10 My invention relates to a removable bar hanger and particularly to a bar hanger for securing a strap or bracelet to a watch case.

15 The object of my invention is to provide a removable bar hanger whereby a loop or eye may be easily and readily attached to a frame or support and readily removed or disconnected therefrom.

20 A further object is to provide a removable bar hanger which is simple in construction, embodying but few parts of simple design, and of such nature and character that the parts may be easily and readily machined or fabricated and at the same 25 time to provide a removable bar hanger which will be efficient and serviceable in operation and one which is particularly adapted for employment with articles of jewelry such as a wrist watch case, which is ordinarily held to the wrist by a strap or bracelet.

30 A further object is to improve generally and enhance the utility of articles of the class to which the present invention pertains, and with the foregoing and other objects in view, my invention consists in the improved removable bar hanger illustrated in the accompanying drawing and hereinafter described and claimed, and in 35 such variations and modifications thereof as will be obvious to those skilled in the art to which my invention relates, it being understood that changes may be made within the scope of what is claimed without departing from the spirit thereof.

40 The preferred embodiment of my invention is disclosed in the accompanying drawing, wherein:

45 Figure 1 is a view in elevation of a wrist watch having a strap secured thereto by my improved removable bar hangers;

50 Figure 2 is an enlarged detail view illustrating the removable bar hanger secured to the frame or arms of the watch case;

Figure 3 is a detail view in perspective 55 of the removable bar;

Figure 4 is a detail view in perspective of the friction pin for holding the removable bar securely in place and at the same time allowing for its ready removal when 60 desired;

Figure 5 is a fragmental view in section of a somewhat modified form of removable bar hanger; and

Figure 6 is a detail view in perspective 65 of the friction pin employed in this modified form of my invention.

Referring specifically to the several views, wherein similar reference numerals designate corresponding parts throughout, the 70 arms A are representative of the lugs upon a wrist watch case or any style or type of frame or support to which it may be desirable to detachably secure a loop or eye, such as, for example, located at the end of the ordinary strap for a wrist watch case.

The arms A are provided with the aligned openings B and which are adapted to nicely receive the removable friction pin D. A bar E is adapted to fit between the 80 confronting faces of the arms A, and has the opening F which extends therethrough of approximately the same size as the openings B so as to align therewith. The removable friction pin D is of such size as to 85 also fit snugly within the opening F of the tube. The body portion of the friction pin D is split as at G and the two resulting side walls H are spread apart, so that this portion of the pin is of relatively greater diameter than the opening 90 F within the removable bar E. The pin D, being formed of resilient metal, is accordingly adapted to engage the side walls of the opening of the removable bar E when 95 forcibly pressed therein.

Thus when it is desired to secure a strap such as K to a wrist watch case L, the strap is provided with the usual loop M at its extremity and the bar E is first inserted 100 within the loop or eye M. The bar is then brought between the confronting arms A and the openings of the arm and bar brought into alignment. The friction pin D is then forcibly thrust through the aligned openings B of the arms and the opening F of the bar until the ends of the pin are flush with the outer walls of the 105

arms, such as illustrated in Figure 2. As the pin is thus forcibly moved into place the side walls H will be compressed and accordingly frictionally engage the side walls of the opening within the bar and thus securely but detachably hold the bar in place and accordingly removably secure the strap K to the frame.

A somewhat modified form of my invention is disclosed in Figures 5 and 6, wherein the friction pin N is provided with either one or both ends O split, as at P, the resulting sides Q of the bar being then forced apart. With this type of friction pin, the removable bar E is first brought into alignment with the openings B of the frame or lugs and the sides Q of the leading end of the friction pin compressed so as to enter the opening B of the arm A. The friction pin is then forcibly moved into position as illustrated in Figure 5. The sides Q will tend to resiliently spring apart and in so doing frictionally engage the side walls of the openings B in the arms and accordingly hold the removable bar E firmly but removably in position.

While my bar hanger as thus constituted

is particularly adapted for wrist watch cases, it is to be understood that it may be used in other relations, such as, for example, when it is desired to secure an eye or loop to a support or frame.

Having thus described and explained my invention, I claim and desire to secure by Letters Patent:

An article of the class described comprising confronting arms provided with aligned openings therein, a removable bar fitting between said arms and provided with an opening extending therethrough, a pin extending through the openings in the arms and the removable bar, said pin provided with a split portion between its ends, and with the resulting side walls spread apart and frictionally engaging the adjacent surrounding walls of said bar and holding said pin in place.

Signed at Riverside in the county of Burlington and State of New Jersey this 9th day of January A. D. 1923.

GEORGE R. MULHOLLAND.

Witnesses:

GEORGE HAISCH,
BERNARD LEVY.
